SPECTACLE TEMPLE

Eugene D. Ditto, Needham, Mass., assignor to Marine Optical Manufacturing Company, Boston, Mass., a corporation of Massachusetts

Filed Dec. 26, 1963, Ser. No. 77,929

Term of patent 14 years

(Cl. D57—1)

FIG. 1

FIG. 3

FIG. 1 is a side elevation view of a temple, showing my new design;

FIG. 2 is an elevation view of the opposite side thereof; and

FIG. 3 is a front perspective view thereof.

The broken line showing of the lens is for illustrative purposes only.

I claim:

The ornamental design for a spectacle temple, substantially as shown and described.
